CLAIM

The ornamental design for a combined squeeze bottle and cap, as shown, and described.

DESCRIPTION

FIG. 1 is a perspective view of a combined squeeze bottle and cap in a first embodiment;

FIG. 2 is a left side view thereof (with the right side being a mirror image thereof);

FIG. 3 is a rear elevation view thereof;

FIG. 4 is a front elevation view thereof;

FIG. 5 is a top plan view thereof;

FIG. 6 is a perspective view thereof in a second embodiment;

FIG. 7 is a left side view thereof (with the right side being a mirror image thereof);

FIG. 8 is a rear elevation view thereof;

FIG. 9 is a front elevation view thereof; and,

FIG. 10 is a top plan view thereof.

The dash-dot-dash broken lines represent the bounds of the combined squeeze bottle and cap. The appearance of any portion of the article between the dash-dot-dash boundary lines forms no part of the claimed design.
